UNITED STATES PATENT OFFICE.

CLYDE G. MORGAN, OF MOUNT VERNON, MISSOURI.

MACHINE FOR PRINTING FROM FILMS OR PLATES.

No. 884,516.

Specification of Letters Patent.

Patented April 14, 1908.

Application filed August 8, 1907. Serial No. 387,659.

To all whom it may concern:

Be it known that I, CLYDE G. MORGAN, a citizen of the United States, residing at Mount Vernon, in the county of Lawrence and State of Missouri, have invented certain new and useful Improvements in Machines for Printing from Films or Plates; and I do declare the following to be a full, clear, and exact description of the invention, such as to enable others skilled in the art to which it appertains to make and use the same.

This invention has relation to new and useful improvements in machines for printing from films and plates, and has for its principal object to provide a simple and economical device of this character, whereby prints may be made from films or plates in a convenient and expeditious manner, and with a minimum of labor.

20 With the foregoing and other objects in view, the invention consists of certain novel features of construction and combination of parts illustrated in the drawings, and particularly pointed out in the appended claims.

25 In the accompanying drawings, Figure 1 is a front end view of a printing machine, constructed in accordance with the invention, the front door removed; Fig. 2 is a side elevation, the front door in position; Fig. 3 is a 30 plan view; Fig. 4 is a central, longitudinal, sectional view, the door closed; Fig. 5 is a detail view of a plate holder, that may be employed in carrying out the invention; and Fig. 6 is a diagrammatic view, showing an 35 arrangement or electrical connection whereby the light employed or used in the casing of the machine for making an exposure may be extinguished when the front door is opened.

40 In the embodiment illustrated, a casing or boxing 1, having its rear end closed by a removable door 2, and having arranged at its front or opposite end a suitable frame 3, is shown. Said frame 3 is provided with open- 45

ings 4 and 5 at its upper and lower end respectively, and with recesses 6 in the inner faces of its sides to receive a suitable glass 6', having arranged over its outer face suitable, flexible black material 7, having a suitable

50 opening 8 in its lower end to expose a corresponding portion of the glass. A suitable roller 9, having a ratchet 10 at one end and a crank 11 at said end is journaled in suitable bearings on top and at the front end of the 55 casing, the crank being journaled in a bracket bearing 12, and the opposite end of the roller

in the free end of a spring 13, secured at its opposite end to the top of the casing. A disk 14 is arranged on the end of said roller, adjacent to said spring, and a spring 15 is attached at one end to the top of the casing, and provided at its opposite or free end with a suitable opening 16, adapted to engage the teeth of said ratchet, for preventing a retrograding movement of said roller 9. A roller 60 17 having circular flanges or end pieces 18 is arranged under the casing and is journaled in position by a rod 19 adapted to be inserted through the roller, and through corresponding apertures of hangers 20, attached to the 65 bottom of the casing in vertical alinement with the bearings, for said first mentioned roller. A door 21 is hinged at its lower end, immediately in front of said glass 6, and is provided entirely across its width in its inner 70 face and near its lower end with a mortise or recess 21', adapted to receive a corresponding board or strip 22, which is flush with the inner face of said door when closed. Two raising members 23 are attached to the said 75 board or strip, pass through the door and are provided with heads 24, adapted to engage engaging members 25 arranged in any suitable manner in front of the door, so that when the door is opened the board or strip will be 80 pressed inwardly by the engagement of the heads of the raising members with the engaging members. An automatically operated button 26 is arranged in the front door, at a suitable point above said board or strip 22 85 and normally projects or protrudes some little distance inwardly of the door, the purpose of which will be disclosed. A light 26' is arranged on top of the casing adjacent to and in rear of the roller 9, and a light 27 in the 90 casing, it being desirous that said light 26' should burn continuously, and the light 27 be extinguished when the door is opened. To accomplish this the following arrangement may be adapted. An extension plug 28. 100 is arranged to be attached to a globe socket. Two wires 29 are connected from this socket to the light 26', establishing a circuit through said light, which will burn no matter whether the door is closed or opened. From said light, a wire 30 runs to the light 27, and from one side of the light 27 a wire 31 runs to a metallic plate 32, attached to the frame at a suitable point. A wire 33 also runs from the light 26 to a metallic plate 34, attached to the 105 outer face of the door and a contact screw works through the plate 34 and is adapted to

engage plate 32 when the door is closed and establish a circuit through the light 27 in the casing. From the arrangement shown it will be seen that light 26' will burn continuously, no matter whether the door is opened or closed, and the light 27 in the casing will be extinguished when the door is opened, as the circuit will thereby be broken. Any other arrangement that fairly falls within the scope of the invention may be employed to carry out the above object.

After the film 35 has been developed and dried one end is attached to the roller 17, located under the casing by slipping it under a fastening wire 36, arranged between the ends of the roller. After rolling the film up tight on this roller, the free end of the same is passed upward through the openings in the frame 3 at the front end of the casing, and is fastened to the roller 9 arranged on top of the casing by a fastening wire or member 37. The machine is then ready for printing, which is accomplished in the following manner: The front door is swung open, and owing to the engagement of the raising member 23, with the engaging members 25, the board or strip 22 is pressed inwardly beyond the inner face of the door, and serves as a support for the sensitized paper, placed on the inner face of the door. The sensitized paper being in this position, the crank 18 is turned until the film comes in proper position over the exposed part of the glass 6. The door is then closed, and the sensitized paper pressed against the film, the circuit through the light 27 being at the same time established, by the light passing through the exposed part of the glass through the film. The door is then swung open, when the sensitized paper falls through the opening at the lower end of the frame into a suitable box or other receptacle, arranged there under. When the door is swung open, the automatically operated button swings into its original position and greatly facilitates in the discharge of the sensitized paper through the opening at the lower end of the frame. As soon as the required number of prints have been made from the film, the crank is turned until the next one comes into position, and the printing process continues until the entire roll has been printed. After the entire film has been used for printing, it is rolled on the roller 9 and removed by detaching the spring 13 from the adjacent end of the roller, and removing the disk 14. In order to accommodate the different sized films, the exposed part of the glass is varied as described.

When it is desirous to print from plates, the glass 6 is removed and a plate holder 38 inserted in its stead. In the drawings, I have shown a form of plate holder which is preferably employed. This plate holder is provided with an opening 39 in its lower end, so arranged as to be on a level with the upper

edge of the board or strip 22 when the paper is placed on the door for printing, so that no matter what size plate is used it will be in position to print. A suitable frame 30 of thin flexible material, such as celluloid, is arranged at the opening in the plate holder to receive the plate, a piece of felt 40 or other suitable material being arranged at the upper end of the frame to prevent the light from passing upward and exposing the sensitive paper.

From the foregoing description, taken in connection with the accompanying drawings, the construction and operation of the invention will be readily understood without requiring a more extended explanation.

Various changes in the form, proportion and the minor details of construction may be resorted to without departing from the principle or sacrificing any of the advantages of this invention.

Having thus particularly described my invention, what I claim as new and desire to secure by Letters-Patent, is:

1. In a machine of the character described, the combination of a casing, a glass removably arranged at one end of the casing, a door hinged to the casing in front of the glass, a spring actuated button, arranged in the door and normally projecting beyond the inner face of the same, a transverse strip arranged at the hinged end of the door in position to engage the glass, and means for raising the strip when the door is swung open.

2. In a machine of the character described, the combination of the casing, a frame arranged at one end thereof, adapted to receive a glass or a plate holder, a door hinged to the casing in position to be received by the frame, a transversely disposed strip mortised in the inner face of the door at its hinged end, a spring actuated button arranged in the door above said strip to normally project beyond the inner face thereof, an electric light arranged in the casing, and means for establishing a circuit through the light, when the door is closed and breaking the circuit when the door is opened.

3. In a machine of the character described, the combination with a casing, of an upright frame arranged at one end thereof, a plate arranged in the frame, said plate having only a portion of its outside face exposed, means for leading a film in front of the glass, an upright door pivoted to the casing in position to swing in a vertical plane in front of the glass and to be pressed against the film, a transversely disposed strip mortised in the inner face of the door, means for raising said strip when the door is swung into open position, an electric light arranged within the casing and connections for establishing a circuit through said light when the door is closed and for breaking the circuit when the door is swung open.

4. A machine of the character specified, embracing a casing, a glass arranged at one end of the casing, an open frame arranged at said end of the casing, the end pieces of the frame being formed with longitudinal openings to receive the ends of the glass and to permit the passage of a film in front of and against the glass, a transversely disposed strip mortised in the inner face of the door, means for raising said strip when the door is swung into open position and means for leading a film in front of the glass.

5. A machine of the character specified, embracing a casing, a glass arranged at one end thereof, an open frame formed with openings in its end pieces to receive the glass and to permit of the passage of a film in front

of the glass, flexible material arranged on the outer face of the glass, the former being formed with an opening to expose a corresponding portion of the latter means for leading a film in front of and against the glass, a transversely disposed strip mortised in the inner face of the door and means for raising said strip when the door is swung 25 into open position.

In testimony whereof I have hereunto set my hand in presence of two subscribing witnesses.

CLYDE G. MORGAN.
